(57) **CLAIM**

I claim the ornamental design for a leg and foot stretching device, as shown and described.

DESCRIPTIONFIG. 1 is a front view of the leg and foot stretching device.
FIG. 2 is a rear view of the claimed design.

FIG. 3 is a left side view of the claimed design.

FIG. 4 is a right side view of the claimed design.

FIG. 5 is a top view of the claimed design; and,

FIG. 6 is a bottom view of the claimed design.

The claimed design is shown with a symbolic break in its length. The appearance of any portion of the article between the break lines forms no part of the claimed design.
